UNITED STATES PATENT OFFICE

165,981

ARTICLE HOLDING RACK FOR TABLES

Earl F. Husted, Kansas City, Mo.

Application August 15, 1949, Serial No. 4,512

Term of patent 7 years

(Cl. D44—24)

To all whom it may concern:

Be it known that I, Earl F. Husted, a citizen of the United States, residing at Kansas City, in the county of Jackson and State of Missouri, have invented a new, original, and ornamental Design for an Article Holding Rack for Tables, of which the following is a specification, reference being had to the accompanying drawing, forming a part thereof.

Fig. 1 is a perspective view of an article holding rack for tables, showing my new design.

Fig. 2 is an end elevational view thereof; and, Fig. 3 is an inverted plan view thereof.

I claim:

The ornamental design for an article holding rack for tables, as shown.

EARL F. HUSTED.
